UNITED STATES PATENT OFFICE.

LESLIE E. HOWARD, OF LA GRANGE, ILLINOIS, ASSIGNOR TO SIMONDS MANUFACTURING COMPANY, OF FITCHBURG, MASSACHUSETTS, A CORPORATION OF MASSACHUSETTS.

INGOT-CASTING MACHINE.

No. 926,489.

Specification of Letters Patent. Patented June 29, 1909.

Application filed July 2, 1908. Serial No. 41,642.

To all whom it may concern:

Be it known that I, LESLIE E. HOWARD, a citizen of the United States, residing at La Grange, in the county of Cook and State of Illinois, have invented certain new and useful Improvements in Ingot-Casting Machines, of which the following is a specification.

This invention relates to ingot-casting machines, and more particularly to machines of that type wherein lateral pressure is applied to the ingot during the cooling of the latter for the purpose of preventing the formation of blow-holes and cavities in the ingots, due to the "separating out" of gases from the steel comprising the ingot during the cooling of the same, and the formation of the defect known as "piping", resulting from the shrinkage of the metal after the outer sides and bottom of the ingot have set and hardened, and while the center is still molten, which condition allows the molten metal from the upper portion of the ingot to feed down and partially replace that drawn toward the sides of the lower portion of the ingot, owing to shrinkage in cooling.

In an application filed by me on the 9th day of March, 1908, Serial No. 419,948, I have disclosed an ingot-casting machine having some features in common with the machine of the present invention, including the provision of means for applying a gradually increasing pressure to the ingot during the cooling of the latter, and means for facilitating the discharge of the ingot after molding through the provision of a removable bottom and retractable sides. In the machine of my present invention I employ a specifically different construction of mold and a different mechanism for yieldably supporting and retracting the movable side walls thereof.

The leading feature of the present invention, so far as it relates to the structure of the mold itself, consists in the employment of a pair of mold-members one of which is fixed and the other of which is movable, both vertically and laterally, each of said members affording two adjacent lateral walls of a rectangular mold. One wall of the movable member is subjected to the action of the hydraulic or other motive agent through which the squeezing or compression of the ingot is effected, while the other wall of the movable member is likewise subjected to a

lateral thrust sufficient to insure a tight closing of the joints between the fixed and movable members of the mold before and during the pouring in and compression of the metal; the retraction of such thrust-applying means permitting also the retraction of this wall sufficiently to release the molded ingot at the proper time and permit it to drop through the bottom of the mold when the closure for the latter has been opened.

My invention, in a practical form in which the same may be embodied, is illustrated in the accompanying drawings, in which,—

Figure 1 is a top plan view of my improved machine; and Fig. 2 is a substantially central vertical longitudinal sectional view through the apparatus, showing also means for applying a graduated pressure to the ingot-compressing cylinders of the apparatus.

Referring to the drawings, 5 designates each of a pair of parallel side-frame members, 6 an end-frame member, and 7 each of a pair of cylinder castings disposed one above the other and constituting in part the other end-frame member of a rectangular main frame 80 of the apparatus, the side members 5 being securely united to the end members 6 and 7 by through-bolts 8. The required tensional strength is secured in the frame by the use of overlapping lateral projections 5^a on the side-frame members 5, and 6^a and 7^a on the end-frame members 6 and 7, respectively. In the castings 7 are formed the cylinder chambers 9, herein shown as two in number, superimposed with their longitudinal axes 90 horizontal and parallel to each other, and slidably fitted with rams or plungers 10 and provided with pipe connections 11 by which they are connected to a source of fluid pressure (not shown) through a pipe 12 controlled by a regulating valve 13, through which the pressure admitted to the cylinders can be varied as desired, the exhaust being effected through a valve 13^a.

Within the frame at the opposite end 100 thereof are arranged one or more vertically disposed molds, herein shown as two in number, disposed side by side, said molds being formed in part by a heavy vertical block or plate 14 forming the stationary part of the 105 two molds, said block having a central inward projection 14^a forming the two inner stationary side walls of the molds, and a forwardly projecting horizontal flange 14^b at its top (Fig. 2) overlying and resting upon the 110

frame-member 6, the opposite edges of this flange being socketed to receive the inner ends of a pair of slotted clamps 15 adjustably secured by bolts 16 to the top of the machine frame, whereby the mold-member 14 is rigidly held in place with capacity for easy removal and replacement when necessary.

17 designates each of a pair of vertical side members of the molds which are the active agents in transmitting the pressure applied to the ingots. These members 17 have integral rectangular extensions 17^a located at their outer edges, which extensions overlap the opposite vertical edges of the stationary mold-block 14, as plainly shown in the plan view, Fig. 1, and constitute the outer side walls of the mold. It will also be observed that the integral extension 14^a of the stationary mold-block 14 similarly overlaps at 20 its inner end the inner adjacent edges of the movable mold-blocks 17. From this it will be seen that the four-sided mold is made up of two vertical mold-blocks or plates each of which provides two adjacent and integral sides of the mold; the mold-box having but two vertical lap joints located in diagonally opposed relation to each other.

Referring now to the means for supporting and actuating the movable mold-members 17 and their rectangular extensions 17^a, 18 designates as an entirety a solid block located approximately centrally of and within the main rectangular frame of the machine and constituting a cross-head between the plungers 10 and the compressing sides 17 of the molds. This cross-head is slidably supported on the main frame by lateral flanges 18^a that overlie the upper edges of the side-frame members 5, and it is guided by vertical ribs 18^b formed on its opposite vertical edges, these ribs engaging the inner side walls of the side-frame members 5, and constituting in part the means for effecting the retraction of the cross-head, as hereinafter described. The rear face of the cross-head 18 is directly engaged by the forward faces of the rams or plungers 10, as best shown in Fig. 2, while its forward face similarly directly engages the mold-members 17, which latter are supported with capacity for limited movement both vertically and edgewise from the cross-head by means of upper and lower arms 19 and 20, respectively, pivoted at 21 and 22, respectively, to the upper and lower faces of the cross-head and projecting over the front face of the latter and provided with inwardly disposed vertical dowels 19^a and 20^a which enter and loosely fit vertical holes or sockets in the upper and lower ends 60 of the mold-members 17. The pivotal character of the supporting arms 19 and 20, and the loose fit of the dowels in the cooperating sockets of the mold-members affords a slight capacity for both vertical and lateral shifting 65 of the mold-members 17 and, of course, of

their integral extensions 17^a. These arms 19 and 20 also constitute the operative connections between the cross-head and mold-members 17 and 17^a for the retraction of the latter when the mold is to be opened or expanded to release the ingot; although the compressing effect is imparted directly to the mold-members from the cross-head by reason of the vertical abutment of the latter against said mold-members. 75

Referring now to the means for applying pressure to the outer lateral mold-members 17^a, with which are included means for effecting the retraction of the compressing mold-members 17 through the cross-head 18 80 after the compression of the ingot has been completed, 23 designates upper and lower pairs of rectangular bars slidably fitted in grooves in the inside surfaces of the side-frame members 5; and attached to the ends 85 of these bars at the forward or mold end of the machine are shoes 24 preferably of steel and possessing a slight degree of transverse elasticity, which shoes engage and ride over transverse wedge-shaped ribs 25 formed on 90 the outer sides of the mold-members 17^a. These bars, with their attached shoes, are given a longitudinal movement by the action of fluid pressure on a differential piston 26 (Fig. 2) in a cylinder 27, attached to the 95 outer rear end of the cylinder castings 7, acting through connections consisting of a piston rod 28, pin 29, cross-bar 30, pins 31 (Fig. 2), vertical equalizing bars 32, and pins 33 connecting the ends of the latter with the 100 bars 23.

The bottoms of the twin mold chambers are closed by a horizontal bottom plate 34 that lies loosely in a movable plate-holder 35. This latter is pivotally mounted at 36 on an 105 arm 37, in turn pivoted at 38 to the depending brackets 39 on the main frame-members 5. The arm 37 is caused to swing approximately 90 degrees on the shaft 38 by the action of fluid pressure in a motor cylinder 110 40 beneath and secured to the main frame, said fluid pressure acting through piston 41 in said cylinder, piston-rod 42, and a longitudinally adjustable pitman 43 pivoted at 44 to a depending extension 37^a of the arm 115 37. The fluid pressure cylinders 27 and 40 are provided with suitable valve-controlled fluid pressure supply and exhaust pipes, indicated at 27^a and 40^a, respectively, adapted to admit the fluid pressure alternately to opposite sides of the pistons of said cylinders at the proper intervals in the operation of the machine, said controlling devices being old and well known, and constituting no part of the present invention. 120

In the operation of the machine, the compressing mold-members 17 are adjusted to the position shown in Fig. 1. The bottom of the mold is then closed by admitting fluid pressure to the right hand end of motor cylin- 130

der 40, which causes the bottom plate 34 to form a closed joint at the bottom end of the vertical mold-members, this operation producing a slight lifting of the integral mold walls 17 and 17^a, thus insuring a tight joint between the bottom plate and all four sides of the mold. The outer lateral mold walls 17^a are then crowded inwardly of the mold by applying fluid pressure to the right-hand end of the cylinder 27, which, through the connections described, forces the shoes 24 forwardly over the inclined faces of the wedges 25, and thus produces tight vertical joints at the diagonally opposite corners of the mold-chambers. Molten metal is then poured into the mold-chambers by hand or by a suitable pouring ladle until the molds are full to within two or three inches of their tops. Fluid pressure is then applied to the cylinder chambers 9 through the supply-pipes 11, causing a longitudinal movement of the plungers, cross-head, and compressing mold-members 17 toward the forward or mold end of the machine, and lessening the cross-sectional area and volume of the mold chambers. This, of course, moves the outer lateral mold walls 17^a in an edgewise direction, but the pressure in the cylinder 27 being maintained during this period, the shoes 24 follow the retracting wedges 25 and thus maintain the pressure upon the walls 17^a while the compressing of the ingot is going on.

The operator carefully watches the exposed top ends of the ingots under treatment and, through the hand valve 13 or other pressure-regulating means, graduates the fluid pressure acting on the plunger so as to effect a sufficient contraction of the cross-section of the ingots during their change from the molten to the solid state, so as to cause the gradually decreasing portion of molten metal to remain always approximately even and of uniform height with the solidifying sides of the ingots. As soon as the top ends of the ingots appear solid, the pressure is increased somewhat more rapidly, causing a slight forging or kneading action to take place throughout the mass of the ingots, and this pressure is maintained until the metal has attained a stable state of crystallization. The desired compression of the ingots having been thus effected, the supply and exhaust of fluid pressure to the motor cylinders 27 and 40 is reversed, thus dropping the bottom plate 34, retracting the shoes 24, and releasing the pressure upon the outer lateral mold walls 17^a, and an instant later retracting the cross-head 18 through engagement of the inner ends of the shoes 24 with the vertical ribs 18^b of the cross-head, which, through the arms 19, simultaneously retracts the compressive mold-members 17. This entirely frees the compressed ingots and leaves them free to drop through and out of the bottoms of the mold-chambers into the space beneath

the machine, or into any suitable receptacles therefor. The molds are then again adjusted and prepared for subsequent operations, as above described.

In practice several of these machines may be provided, placed side by side alongside of a melting furnace, or between two furnaces, or otherwise, as may be most convenient in each instance, with their mold ends all in the same relative positions, and the pouring of the molten metal into the molds is best accomplished by means of a pouring ladle in a manner at present well understood and extensively practiced in connection with the production of crucible steel.

80

I claim:

1. In an ingot-casting machine, a mold of substantially rectangular cross-section composed of a stationary mold-member forming two integral adjacent sides of the mold, and a movable mold-member forming the other two integral adjacent sides of the mold, in combination with means for applying pressure to one wall of said movable member whereby to compress the ingot during cooling thereof, and means for simultaneously maintaining pressure upon the other wall of said movable mold-member whereby to maintain tight joints between the fixed and movable mold-members during the compression of the ingot, substantially as described.

2. In an ingot-casting machine, the combination with a frame comprising rigidly connected side and end members, of a mold mounted in one end of said frame and comprising fixed and movable members, a cylinder and plunger therein mounted in the other end of said frame, a cross-head slidably mounted in said frame between said plunger and movable mold-member, and connections between said cross-head and movable mold-member comprising arms pivoted to the upper and lower sides of said cross-head and projecting over the upper and lower ends of said mold-member, said arms having inwardly projecting pins loosely engaging sockets formed in said mold-member, substantially as described.

3. In an ingot-casting machine, the combination with a containing frame, of a mold mounted in one end of said frame comprising fixed and movable members each containing two adjacent integral side walls of a rectangular mold, a cylinder and plunger therein in the other end of said frame, a cross-head slidably mounted in said frame between said plunger and movable mold-member, connections between said cross-head and one wall of said movable mold-member permitting a limited extent of both vertical and lateral movement of the latter, and means for applying pressure to the other wall of said movable mold-member to effect tight joints between the latter and the fixed mold-member, substantially as described.

130

4. In an ingot-casting machine, the combination with a rectangular frame comprising rigidly connected side and end members, of a mold mounted in one end of said frame, said 5 mold comprising a stationary member having a horizontal flange whereby it is supported upon one of the cross-members of said frame and a member movable toward and from said stationary member, means for 10 holding said stationary mold-member in place, means contained within said frame for applying pressure to said movable mold-member, and means for retracting said movable member after compression of the ingot 15 to release the latter, substantially as described.
5. A mold frame comprising one-piece side and end castings rigidly united, said side and end castings, respectively, having overlapping lateral projections engaging each other in a manner to resist longitudinal strain upon the frame, in combination with a mold in said frame and means for applying pressure thereto.
6. A mold frame comprising one-piece side 25 and end castings rigidly united, one of said end castings having a power cylinder cast therein, and said side and end castings, respectively, having overlapping lateral projections engaging each other in a manner to resist longitudinal strain upon the frame, in combination with a mold having a movable side member, a plunger in said cylinder, and power-transmitting connections between said 30 said plunger and movable mold-member. 85
